(74) Attorney, Agent, or Firm—William J. Sapone;
Coleman Sudol Sapone, P.C.(57) **CLAIM**

The ornamental design for a cap opener, as shown and described.

DESCRIPTION

FIG. 1 is a rear perspective view of the cap opener showing my new design;

FIG. 2 is a cross section view taken along line 2—2 in FIG. 1;

FIG. 3 is a front perspective view thereof engaged with a pull ring of a can. The broken lines showing a portion of a beverage can is for illustrative purposes only and forms no part of the claimed design; and,

FIG. 4 is a partial view of the cap opener engaged to a bottle cap pull tab.

The broken lines showing a top portion of a bottle is for illustrative purposes only and forms no part of the claimed design.
